CLAIM

The ornamental design for a heated light pad, as shown and described.

DESCRIPTION

FIG. 1 is a top perspective view of a heated light pad;
 FIG. 2 is a bottom perspective view of a heated light pad;
 FIG. 3 is a top view of a heated light pad;
 FIG. 4 is a bottom view of a heated light pad;
 FIG. 5 is a left side view of a heated light pad;
 FIG. 6 is a right side view of a heated light pad;
 FIG. 7 is a front view of a heated light pad; and,
 FIG. 8 is a rear view of a heated light pad.

The broken lines in the drawings illustrate portions of the heated light pad that form no part of the claimed design.

1 Claim, 6 Drawing Sheets(56)
